UNITED STATES PATENT OFFICE

155,274

DESIGN FOR A TILT-BACK CHAIR

Charles Eames, West Los Angeles, Calif., assignor
to Evans Products Company, Detroit, Mich., a
corporation of Delaware

Application March 27, 1947, Serial No. 137,930

Term of patent 14 years

(Cl. D15—1)

To all whom it may concern:

Be it known that I, Charles Eames, a citizen of the United States, residing at West Los Angeles, in the county of Los Angeles and State of California, have invented a new, original, and ornamental Design for a Tilt-Back Chair, of which the following is a specification, reference being had to the accompanying drawings, forming a part thereof.

Figure 1 shows a side elevational view of the tilt-back chair, embodying my new design;

Figure 2 shows a front elevational view thereof.

Figure 3 shows a rear elevational view thereof.
Figure 4 shows a perspective view thereof.

I claim:

The ornamental design for a tilt-back chair, as shown.

CHARLES EAMES.
